UNITED STATES PATENT OFFICE.

AUGUST MUELLER, OF NEW YORK, N. Y.

HATBAND-LOOM.

1,351,533.

Specification of Letters Patent. Patented Aug. 31, 1920.

Application filed August 20, 1919. Serial No. 318,700.

To all whom it may concern:

Be it known that I, AUGUST MUELLER, a citizen of the United States, residing at New York, in the county of New York and State of New York, have invented certain new and useful Improvements in Hatband-Looms, of which the following is a specification.

This invention is in the nature of improvements in looms for making hat bands.

Long experience in the manufacture of hat bands has revealed deficiencies in such looms and the present invention is intended to correct such deficiencies. The most important part of such looms is the so called "quick change motion" for elevating the shafts, and the present invention is an improvement thereon.

It is the general requirement in the art to manufacture men's hat bands of the least material and of good quality, in contradistinction to the manufacture of ribbons. The silk warp used is selected of a very low twist and the warp to weave with little weight. This circumstance involves the danger of manufacturing goods of a very bad quality, and in order to avoid this, the idea of the quick change motion has been developed. This part appears to be the most important one in the looms used and needs a decided improvement, the present system being a rigid unchangeable one. According to my improvements the system is made adjustable in every direction.

In order that the construction and operation thereof may be readily understood, I have illustrated an improved embodiment of the invention in the accompanying drawing, and will now proceed to fully describe the same in connection with said drawing, in which—

Figure 1 represents a view of parts of the loom in side elevation, other parts being broken away;

Fig. 2, a view in perspective of the same parts as shown in Fig. 1, showing some of the parts broken away in Fig. 1;

Fig. 3, a detail sectional view showing the two-armed lever;

Fig. 4, a detail view in end elevation, of the treadles and their support and springs, looking at the left-hand end of Figs. 1 and 2;

Fig. 5, a detail view, in horizontal section, through the right-hand end of Fig. 1.

Like reference characters mark the same parts in all of the figures of the drawing.

Referring specifically to the drawings, from which are omitted most of the parts not improved by this invention, instead of the larger pulley generally used in such looms I have made a two-armed lever 6 engaging the square rod 7, which lever has several advantages over the pulley. First, no leather straps, which frequently break, are necessary. The lever 6 is connected with the shaft wires by strong wires 8, and simultaneously the two arms are used as hammers, being provided with sliding weights 9, and by hanging the strong wires into different holes, I obtain a higher or lower stroke of the shafts. The smaller pulley usually used I have replaced by two strong screw bolts 11 set into the rod, which I can screw out of or into the rod as I think advisable and these bolts are also in direct connection with the treadles 12 by wires 13, without the intermediary of leather straps. Thus the loom will work toward all directions as may be desired. Into each of the treadles 12 I have inserted a piece 14 by means of two bolts 15, whereby the treadles may be moved longitudinally for two or three inches toward the rear or toward the front. By hooking the shaft wire into a hole which is still more distant from the axle, and screwing the screw bolts 11 toward the inside, and I produce a very quick motion of the shafts. Any one of the treadles may be adjusted or displaced. A new treadle guide 15 in which movable springs work on loose iron bolts 16. When the treadle goes up the bolt 16 also goes up and compresses the spring, which naturally expands again and carries the treadle and shaft back into the correct position. This guide is very important for the good working of the loom for the manufacture of hat bands which are well covered, and show a good luster.

The wires 8 pass over pulleys 18 and down, being connected to the harness 19, of any well known construction, so that the harness will be operated by the movement of the two armed lever as the square rod 7 is reciprocally rotated.

By means of the constructions described, I fully carry out the described objects of the invention, and I desire it to be understood that I do not confine myself to the exact mechanisms described, but may make changes and variations therein, without departing from the spirit and scope of the invention.

Having thus fully described my invention, what I claim as new and desire to secure by Letters Patent of the United States is:—

1. The combination with a shaft, of adjustable arms thereon, treadles, and connecting wires between the arms and treadles whereby the arms are operated by the reciprocal movements of the treadles, supports for the treadles comprising loosely mounted vertical slidable bolts and springs coiled around the bolts, said bolts being mounted in an an-

gular frame, and the ends of the treadles engaging under the bolts.

2. The combination with a shaft, of a double-ended arm centrally mounted thereon and having a series of holes in each end, hammers adjustably mounted on the arm near each end, a loom harness, and wires connected from said holes and passing over pulleys to the harness. 15 20

In testimony whereof I affix my signature.

AUGUST MUELLER.
